Primary Examiner — Ricky Pham(74) *Attorney, Agent, or Firm* — Venable LLP; Steven J. Schwarz(57) **CLAIM**

The ornamental design for a blender control panel, as shown and described.

DESCRIPTION

FIG. 1 is a perspective view of an embodiment of a blender control panel of the claimed design;

FIG. 2 is a front elevational view thereof; and,

FIG. 3 is a top plan view thereof.

The features shown in broken lines, including the text and symbols on the control panel, are environment only and not part of the claimed design.

1 Claim, 3 Drawing SheetsFIG. 1

FIG. 2

FIG. 3
